UNITED STATES PATENT OFFICE.

ROBERT H. LONG, OF PHILADELPHIA, PENNSYLVANIA.

IMPROVED ARRANGEMENT OF STEAM-ENGINES FOR PROPELLING STREET PASSENGER-CARS.

Specification forming part of Letters Patent No. 26,911, dated January 24, 1860; Reissue No. 1,125, dated January 15, 1861; Reissue No. 1,254, dated January 7, 1862.

DIVISION B.

To all whom it may concern:

Be it known that I, ROBERT H. LONG, of the city and county of Philadelphia, and State of Pennsylvania, have invented a new and improvement in the mode of propelling railway-cars by steam, which is also applicable to the propulsion of carriages by steam upon roads and to the propulsion of carriages by locomotives; and I do declare that the following is a full, clear, and exact description of the same, reference being had to the accompanying drawings, forming part of this specification, in which—

Figure 1 is a side view, partly in section, of the front portion of a railway car having my improvement applied. Fig. 2 is a plan of the same.

Similar letters of reference indicate corresponding parts in the two figures.

This invention relates to the transmission of the power of the engine to the driving-axle of a railway car, carriage, or locomotive by means of gearing; and it consists in the attachment of the driving-pinion to the framing of the engine in such a position, as hereininafter described, is that its axis is in, or nearly in, the same plane with the driving-axle of the car, carriage, or locomotive, whereby, whenever the engine is jolted, it causes a slight movement of the driving-pinion around the cog-wheel, which derives motion from it without disturbing the gearing, and obviates any injurious effects upon the engine.

A is the platform or main frame of the car, carriage, or locomotive. B is the boiler. C

D E is the engine, having its frame C erected upon the platform A and having its crank-shaft E arranged with its axis parallel with and in, or nearly in, the same horizontal plane with the axis of the driving-axle G. The crank-shaft E has the driving-pinion F fast upon it and so attaches the said pinion to the frame C of the engine and to the connecting-rod D, and the driving-axle G has fast upon it the cog-wheel H, with which the pinion gears.

The cog-wheel H is of greater size than the pinion F, the object of which is to obtain by a smaller engine running at a high velocity as much power as can be obtained by a larger engine whose crank makes but one revolution for every one of the driving axle, and thereby to save much weight, which is of especially great advantage in the propulsion of a car or carriage by an engine which it itself carries. Such a system of gearing would be liable to serious objections were it not for the arrangement of the crank-shaft E with its axis in, or nearly in, the same horizontal plane with the axis of the driving-axle G.

What I claim as my invention, and desire to secure by Letters Patent, is—

Transmitting the power of the engine to the driving-axle by means of a driving-pinion, F, attached to the frame of the engine, and arranged relatively to the driving-axle, to operate substantially as herein specified.

ROBT. H. LONG.
